UNITED STATES PATENT OFFICE.

CARL ENGBERG, OF ST. JOSEPH, MICHIGAN.

ROTARY ENGINE.

SPECIFICATION forming part of Letters Patent No. 597,274, dated January 11, 1898.

Application filed May 6, 1897. Serial No. 635,349. (No model.)

To all whom it may concern:

Be it known that I, CARL ENGBERG, of St. Joseph, in the county of Berrien and State of Michigan, have invented a new and Improved 5 Rotary Engine, of which the following is a full, clear, and exact description.

The object of the invention is to provide a new and improved rotary engine which is simple and durable in construction, arranged 10 to utilize the motive agent to the fullest advantage, and constructed for direct connection with high-speed machines, such as dynamos, &c.

The invention consists principally of a pair 15 of cylinders opening into each other at their peripheral surfaces, pistons mounted to turn concentrically in the said cylinders and in peripheral contact one with the other, piston-heads secured on the said pistons and adapted 20 to pass one the other at recesses in the peripheries of the pistons, and a valve-gear for controlling the admission and exhaust of the steam to and from the said recesses.

The invention also consists of certain parts 25 and details and combinations of the same, as will be fully described hereinafter, and then pointed out in the claims.

Reference is to be had to the accompanying 30 drawings, forming a part of this specification, in which similar characters of reference indicate corresponding parts in all the figures.

Figure 1 is a perspective view of the improvement. Fig. 2 is an enlarged sectional side elevation of the same on the line 2 2 in 35 Fig. 3. Fig. 3 is a transverse section of the same. Fig. 4 is a like view of the steam-chest and inlet-valve. Fig. 5 is a perspective view of the inlet-valve. Fig. 6 is an end elevation of the gear-wheel and its locking 40 device for the shaft. Fig. 7 is a plan view of the same, and Figs. 8 and 9 are perspective views of the piston-valves.

The improved rotary engine is provided with two cylinders A and A', opening into each 45 other at their peripheral surfaces, as plainly indicated in Fig. 3, the cylinders being provided with a suitable base A² for attaching the engine to a foundation.

In the cylinders A and A' are mounted to 50 turn concentrically the pistons B and B', respectively secured on shafts C and C', respectively mounted to turn in suitable bear-

ings in the heads of the cylinders as well as in outside bearings, as indicated in Fig. 1. The shafts C and C' are connected with each other 55 by the gear-wheels D and D', of which the gear-wheel D' is secured directly on the shaft C', while the gear-wheel D is loose on its shaft C, and is provided on its outer face with a lug D², projecting into the recess E' of a locking-wheel E, secured to the shaft C. A screw D³ is held adjustably in the lug D² and abuts with its ends on the side walls of the recess E', so that the gear-wheel D can be adjusted 60 on the locking-wheel E to bring the pistons B and B' in proper relation to each other, at the same time permitting the rotary motion of one shaft to be transmitted to the other. The pistons B and B' are provided with piston-heads B² and B³, respectively dovetailed 70 in the body of the pistons, as plainly indicated in Fig. 3, and adapted to pass each other in recesses B⁴ and B⁵, respectively formed in the pistons B' and B, respectively.

The outer ends of the piston-heads B² and 75 B³ are segmental and fit against the inner surfaces of the cylinders A and A', and the sides of the said piston-heads are curved to readily pass each other in the recesses B⁴ and B⁵, as above mentioned and as will be readily 80 understood by reference to Fig. 3. The ends of the pistons, as well as the outer faces thereof and the cylindrical heads adjacent to the pistons, are provided with suitable packings to prevent leakage of steam. (See Figs. 85 2 and 3.) The recesses B⁵ and B⁴ are connected by ports a and b with annular recesses B⁶ and B⁷, formed in the pistons B and B', as plainly shown in Figs. 2 and 3, and into these recesses extend the sleeves F and 90 F', respectively mounted to turn loosely on the shafts C and C', the sleeves being provided within the said recesses with lugs F² and F³, respectively extending to the peripheral surfaces of the recesses B⁶ and B⁷. 95 The outer end of the sleeve F is provided with a hand-lever H under the control of the operator and adapted to be locked to a notched segment H', secured to the head A³ for the cylinders A A'. The outer ends of 100 the recesses B⁶ and B⁷ register with the ports c and d, formed in disks G and G', respectively secured to the inside of the cover A³, formed with ports e and f, registering with

the ports *c* and *d* and opening into a steam-chest *I*, containing an inlet-valve *J*. (See Fig. 4.) This inlet-valve *J* is provided with a lug *J'*, having a port *g*, leading to the inside of the valve *J*, one end of which is connected with the steam-supply pipe *K*, leading to a boiler or other suitable source of steam-supply. On the stem of the valve *J* is secured a handle *J*², under the control of the operator, to turn the said valve *J*, so as to move the lug *J'* into a cut-off position, as shown in Fig. 4—that is, with the port *g* between the entrance ends of the ports *e* and *f*, opening into the chest *I*. The handle *J*² then stands in a vertical position, as indicated in Fig. 1, and steam is cut off from the ports *e* and *f*. Now when the operator turns the handle *J*² to the left the port *g* then connects with the port *e* to admit steam into the said port, and by the port *c* into the recess *B*⁶, from which the live steam can pass through the port *a* into the recess *B*⁵ to act on the piston *B*³ therein to rotate the pistons in the directions of the arrows *a'*. The steam in front of the piston-heads *B*² and *B*⁸ can then pass through the port *b* into the recess *B*⁷, and from the latter, by the ports *d f*, into the steam-chest *I*, around the valve *J*, to the steam-exhaust pipe *K'*, attached to the top of the said chest. When it is desired to reverse the engine, the operator moves the handle *J*² in the opposite direction—that is, to the right, so as to move the lug *J'* to the left to bring the port *g* in register with the port *f*. Steam can now pass down the latter, through the port *d*, into the recess *B*⁷, and from the latter, through the port *b*, into the cylinder *A'* to act on the piston-heads *B*⁸ *B*² to turn the piston in the inverse direction of the arrows *a'*.

It will be seen by reference to Fig. 2 that the recesses *B*⁶ and *B*⁷ are connected by small channels *B*⁸ with the rear ends of the pistons to equalize the pressure on the pistons at both ends, so as to cause the pistons to run easy and without undue friction.

By moving the hand-lever *H* the sleeve *F* is turned to cut off the steam at different points during the revolution of the piston. The packing-rings set into the head *A*³ abut against the faces of the pistons *B*², and are held in place by segments extending into the head *A*³ and traveling in a groove inside of the packing-rings that fit against the pistons *B* and *B'*. The segments on the packing-rings keep the latter from slipping out of the piston-heads when leaving the walls of the cylinders.

Having thus fully described my invention, I claim as new and desire to secure by Letters Patent—

1. A rotary engine, comprising a pair of cylinders opening into each other at their peripheral surfaces, pistons mounted to turn in the said cylinders and in peripheral contact one with the other, piston-heads on the said pistons and adapted to pass one the other at recesses in the peripheries of the said pistons, means for admitting and exhausting the steam to and from the said cylinders by way of the said pistons, and cut-off valves within the said pistons and under the control of the operator, as set forth.

2. A rotary engine, comprising a pair of cylinders opening into each other at their peripheral surfaces, pistons mounted to turn in the said cylinders and in peripheral contact with each other, piston-heads secured on the said pistons and adapted to pass each other at recesses in the peripheries of the said pistons, cut-off valves arranged in recesses in the said pistons and connected by ports in the said pistons with the interior of the cylinders, and an admission and exhaust valve connected with ports leading to the said recess, substantially as shown and described.

CARL ENGBERG.
